BUS BAR DUCT

Herman J. Hammerly, Plainville, Conn., assignor
to The Trumbull Electric Manufacturing Com-
pany, Plainville, Conn., a corporation of Con-
necticut

Application January 29, 1949, Serial No. 574

Term of patent 14 years

(Cl. D26—1)

To all whom it may concern:

Be it known that I, Herman J. Hammerly, a citizen of the United States of America, residing at Plainville, county of Hartford, State of Connecticut, have invented a new, original, and ornamental Design for a Bus Bar Duct, of which the following is a specification, reference being had to the accompanying drawing, forming part thereof.

Fig. 1 is a perspective view of a bus bar duct showing my new design; and

Fig. 2 is a fragmentary view of Fig. 1 as seen from another angle.

I claim:

The ornamental design for a bus bar duct, substantially as shown.

HERMAN J. HAMMERLY.
